UNITED STATES PATENT OFFICE.

JOHN J. ROBSON, OF ST. LOUIS, MISSOURI.

PISTON-VALVE.

Specification of Letters Patent. Patented Dec. 11, 1917.

1,249,506.

Application filed December 22, 1916. Serial No. 138,405.

To all whom it may concern:

Be it known that I, JOHN J. ROBSON, a citizen of the United States, residing at St. Louis, State of Missouri, have invented certain new and useful Improvements in Piston-Valves, of which the following is a full, clear, and exact description, reference being had to the accompanying drawings, forming a part hereof.

10 My invention has relation to improvements in piston-valves; and it consists in the novel features of construction more fully set forth in the specification and pointed out in the claims.

The present invention is in the main directed to improvements in piston-valves for gasolene and explosive engines generally, though not necessarily restricted thereto. The object of the invention is to provide 20 such a valve with suitable packing rings, at the same time maintaining between the rings and the ports controlled by the valve such a relation as to make it impossible for the rings to enter the ports and thereby impede the movements of the valve. The advantages of the invention will be fully apparent from the following detailed description in connection with the accompanying drawings in which—

30 Figure 1 represents a middle longitudinal sectional view of an explosive engine cylinder and valve casing, with sectional views of the valve-actuating mechanism, parts being in elevation; Fig. 2 is a combined cross- 35 section and plan on the zig-zag line 2—2 of Fig. 5; Fig. 3 is a detached elevational view of the piston-valve, parts being in section; Fig. 4 is an end view of the piston-valve stem and bottom plan of the disk 40 which serves as a bearing for the controlling spring; Fig. 5 is a side elevation of the valve with casing partly broken away; and Fig. 6 is a sectional view of an engine cylinder showing the application of two 45 valves, one of them being the intake and the other the exhaust valve.

Referring to the drawings, and for the present to Figs. 1 to 5 inclusive, 1, represents the cylinder of a conventional explosive engine, 2 the piston thereof, and 3 the spark-plug as well understood in the art. In this type of engine the intake valve is in alignment with the spark-plug, such valve being either of the puppet or piston variety as fully understood in the art. A piston-valve without packing rings is open to

the objection of leakage, and the puppet valve requires frequent regrinding to insure proper seating. These objections are overcome by my present improvement 60 wherein the piston-valve 4 is provided with one or more packing rings 5 of the well known split and resilient band type deposited in annular grooves α on the periphery of the valve (Fig. 3). The packing 65 rings while insuring a tight fit between the valve and its cylinder or casing 6, require a special disposition of ports σ in order that the combined area of the ports shall be sufficient to accommodate the explosive mixture 70 of air and gas where an intake valve is concerned, or to accommodate the exhaust gases where an exhaust valve is concerned. The ports must have a longitudinal dimension (that is, a dimension parallel to the 75 axis of the valve or axis of the valve cylinder) in excess of the width of the groove α or the packing ring 5, and their number must be sufficient to provide the required 80 number of partitions or division walls w between the ports to engage the outer faces of the packing rings at a sufficient number of points to prevent the rings from entering the ports and impeding the movements of the valves. In other words, there 85 must be sufficient number of partitions w between the circularly disposed ports σ to prevent the packing rings 5 from spreading. This necessarily results in materially reducing 90 the thickness or circular dimension of the partition; and since in this type of engine a considerable degree of heat is developed in the region of the spark-plug and valve, some provision must be made to give the partitions w sufficient body to prevent 95 the same from being destroyed or burnt out by the excessive temperature in the explosion chamber. In the present embodiment 100 of my invention I provide the necessary body or cross-section for the partitions by extending them radially outward beyond the periphery of the valve cylinder, whereby they form a series of ribs on the outside 105 of the valve cylinder as shown in Fig. 2, these ribs having ample cross-section to withstand the heat. This arrangement dispenses with the necessity of increasing the thickness of the valve-cylinder walls, thereby reducing the weight of metal entering into the casting forming the cylinders for 110 the piston and piston valve. Like the majority of valves of this class, that here shown

is actuated in one direction by a cam 7 on the cam-shaft 8, and intermediate connections shown in Fig. 1 and well understood in the art, and in the opposite direction by 5 a spring 9 whose lower end is supported on the movable abutment or disk 10 resting on a split ring 11 carried in an annular groove near the bottom of the valve-stem 12.

In Fig. 6 is shown a portion of an engine 10 cylinder C showing the application of two valves V and V' (intake and exhaust respectively), the valves being in axial alinement, and in this respect differing from the arrangement shown in Fig. 1 where the exhaust valve (not shown) is behind the intake. The invention is of course not restricted to piston valves (intake or exhaust) of explosive engines, but may be applied to piston valves generally. Features shown 15 but not alluded to are well understood in the art and require no description in the present connection. The operation is the same as that of any other valve in the type of engine here illustrated and need not be 20 repeated herein, the invention being concerned merely with the valve and its casing.

Having described my invention what I claim is:

In combination with a piston-valve provided with peripherally disposed annular 30 resilient packing rings, a casing or cylinder having walls provided with a series of circularly disposed ports across which the valve reciprocates, the partitions between the successive ports being extended radially 35 beyond the periphery of the valve cylinder a distance sufficient to give them the necessary body to withstand the heat, the dimensions of the ports in the direction of the valve axis being elongated and in excess of 40 the width of a packing ring and substantially equal to the thickness of the piston, and the number of ports being such as to afford a sufficient number of partitions to engage a packing ring and prevent the latter from entering the ports.

In testimony whereof I affix my signature, in presence of two witnesses.

JOHN J. ROBSON.
